UNITED STATES PATENT OFFICE.

WILLIAM H. SPENCER, OF BOGOTA, NEW JERSEY, ASSIGNOR TO I. P. FRINK, INC., OF NEW YORK, N. Y., A CORPORATION OF NEW YORK.

LIGHTING FIXTURE.

Application filed October 29, 1925. Serial No. 65,639.

This invention relates more especially to lighting fixtures for providing illumination of variable intensity in homes and other places for which such fixtures may be 5 adaptable.

One of the objects of my invention is to provide an improved construction in lighting fixtures of this character whereby an evenly diffused illumination may be obtained in a simple and effective manner 10 without spots or shadows. By means of my improved construction a perfectly even light may be diffused upon and thru the light-transmitting panels of said fixture, no matter how translucent they may be or how 15 delicately they may be tinted or decorated.

Another object of invention is to provide a light fixture of improved construction whereby the illuminating effects from light 20 sources of different character and intensity may be utilized separately or in conjunction.

My invention contemplates furthermore, an improved construction for lamp fixtures 25 in which the illumination may be derived from light-sources out of the line of vision.

Other and particular objects of invention will appear in the specification and be 30 pointed out in the appended claims, reference being had to the accompanying drawings in which—

Figure 1 is a side elevation of one embodiment of my invention, parts being broken away and parts shown in section;

Figure 2 is a horizontal section of the same on a plane immediately above the line-filament lamps which are shown in plan;

Figure 3 is a horizontal section of another embodiment of my invention, parts being 40 broken away and parts being shown in plan;

Figure 4 is an enlarged fragmentary plan view of the bottom frame and panels according to this adaptation of my invention;

Figure 5 is an enlarged section on the line 45 5—5, Figure 3;

Figure 6 is an enlarged vertical section of one side of an embodiment similar to that shown in Figure 3;

Figure 7 is a side elevation of a modification, parts being broken away and parts shown in section; and

Figure 8 is an axial section of another embodiment, parts being shown in elevation.

According to the adaptation of my invention shown on Figures 1 and 2 of the

drawings, line-filament lamps 1 have their opposite ends mounted in terminal sockets 2, said sockets being mounted upon the top plates 3 of a polygonal lamp-supporting frame. According to the present embodiment of my invention, said frame forms a hollow rectangular square of which each side or section is triangular in cross-section as formed by the top plate 3 and oppositely disposed sides 4 and 5. Said top plate 3 is inclined downwardly and outwardly 60 toward the lower inner corner of a housing which, as shown, comprises a lower rectangular molding 6 of a sheet metal, an upper rectangular molding 7, a top wall 8, and corner pieces 9 which rigidly unite the upper and lower moldings. The lower molding 6 is provided with an inwardly-presented flange 10 upon which rests a glass panel 11 which may be transparent, translucent 65 to any desired degree, tinted, or decorated. The outer edges of said panel 11 is disposed below the lamp-supporting frame, said panel being confined thereby. Within the channeled upper edge of each side of the lower molding 6, is seated a side panel 12, the upper edge of said panel being similarly embraced by the channeled lower edge of the upper molding 7 while the ends of said panels are supported by the corner pieces 9. A reflector may be arranged above the upper edges of the side panels 12 by providing a reflecting surface on the underside of the top wall 8. Light emitting means arranged below the top wall 8, comprise, 70 according to the present embodiment of my invention, a cluster of lamps 13 projecting from a quadruple socket 14, said lamps being preferably disposed within the dihedral angles formed by the side panels 12. If 75 desired, the top wall 8 may be rigidly mounted as for example, by being secured to the ceiling of a room. For convenience in care and for the replacement of parts, the lamp housing may be 80 constructed in movably connected sections. For example, the upper molding 7 may be connected to the fixed top wall 8 by means of a hinge 15 which permits the bottom and side walls of the housing to swing downwardly and away from the cluster-lamps 13. When thus constructed suitable locking screws 16 may be provided for holding the housing parts together under normal conditions of use shown in Figure 1. Extend- 85 90 95 100 105 110

ing around and conforming to the inner perimeter of the lamp-supporting frame so as to cut off the direct light rays from the lamps 1, from the bottom panel 11, is an opaque strip or flange 17 the line-filaments employed in this embodiment of my invention being therefore arranged below the vision line.

In Figures 3 to 6 inclusive, I have shown 10 an arrangement of hidden light-sources extending radially from a common center, said light-sources being preferably line-filament lamps. According to this embodiment of my invention, the lamp-housing may be 15 made substantially cylindrical in contour by constructing it with a plurality of part-circular panels 20. As shown in Figure 3, the vertical edges of these curved panels 20 may be disposed in channeled sections 21, 20 21, arranged in pairs for this purpose and rigidly secured above to an upper frame or molding 22, the lower ends of said sections 21, 21, being secured to a circular frame or channel 23 within which the bottom edges 25 of panels 20 are seated. In this adaptation of my invention, the upper section of the fixture comprises the upper frame or molding 22 provided with a top wall 24 having its inner surface adapted to serve as a reflector, the lateral wall including panels 20 and channels 21, and the circular bottom frame or channel 23. Hinged to this upper section by a pintle 25, is a bottom section comprising a circular frame or molding 26, 30 31 a plurality of panel sectors 27, a central cap or hub 28, and a plurality of radially disposed lamp supports or ribs rigidly uniting the cap or hub 28 to the circular frame or molding 26.

According to Figure 5, each of the radial lamp-supports or ribs comprises a channeled section 29 provided with outwardly presented flanges 30, 30, upon which rests the approximately radial edges of the sector panels 27. An inverted channeled section 31 arranged within each section 29 provides a flat plate or support upon opposite ends of which are arranged suitable lamp sockets 32, 32. In said sockets are mounted the 45 opposite ends of line-filament lamps 33. A transverse section of one of these lamps is indicated in Figure 5, the line of vision with respect to the filament 34 thereof, extending over the upper edges of plates or flanges 35 50 which have their lower edges interposed between the flat sides of channels 29 and 31.

According to the embodiment shown in Figure 7, an upper section 40 similarly constructed to the upper section shown in Figures 3 to 6, may have a hinged connection 41 with a lower section 42 which is similarly constructed to that shown in Figures 3 to 6 except that the line-filament lamps 43 are 60 arranged on downwardly inclined axes with respect to a common center. A releasable

catch or fastening 44 may serve to hold the sections together under normal operating conditions.

By the elimination of side wall panels 20 shown in Figure 7, a more compact arrangement may be had as shown in Figure 8 according to which the light-sources 45 are arranged on radial inclined axes with respect to a central light-cluster 46 depending from a top reflector wall 47. The movable lamp-supporting frame in this embodiment of my invention, is pivotally supported at 48 and provided with a releasable fastening 49. Each of the line-filament lamps 43 and 45 with its underlying radial support, is substantially similar to that shown in Figure 5.

For convenience in explanation and with a view to rendering the underlying principle of my invention more readily understood, I have more especially confined the foregoing 85 description to the embodiments shown on the accompanying drawings. It will be understood, however, that the particular details shown and described are to be taken as illustrative forms in which the elements of my 90 invention may be made to appear. Thus, for example, with respect to the type and numbers of lamps employed, shapes of the fixture, and general arrangement of parts, the terms occurring in the claims are to be 95 taken in a generic sense. While line-filament and tubular lamps are preferably employed in connection with the lower framework of the fixture since it thereby becomes possible to make such lower framework of 100 smaller size, it will be understood that other types of lamps may be used to secure broadly similar results without departing from the principle of my invention. Furthermore, the fixture may be made of any desired shape 105 such as round, square, hexagonal, etc., etc., while the relatively-movable sections of the fixture may be connected at any suitable point or in any suitable manner as may be found desirable in any particular installation.

As an illustration of the advantages to be derived from an installation which embodies the hereinbefore described features, it may be noted that when the central cluster of 115 lamps is not in use, a soft indirect light may be had from the other light-sources which are preferably line-filament lamps arranged to be hidden by the lower frame or molding 6. This holds true even tho transparent 120 glass be employed for the side and bottom light-transmitting panels. Under these conditions, a perfectly even light is diffused on and thru the glass panels and whatever the translucent property of the glass may be 125 and however delicately it may be tinted or decorated, there will be no light spots or shadows to be observed. When a light of higher intensity is desired, the central lamp or cluster may be switched on separately or 130

in combination with the masked line-filament lamps.

I claim—

1. In a lighting fixture, the combination with a housing provided with adjacently-disposed light-transmitting panels and a frame member supporting the adjacent edges of said panels, of a light source mounted upon said frame member, means for cutting off the direct light rays from said light source to one of said panels, and a reflector cooperatively arranged with respect to said light source and the last-mentioned panel.

2. In a lighting fixture, the combination with a housing provided with two light-transmitting panels arranged at angle to each other, of a light source arranged in the angular space between said panels and adjacent to contiguous edges of said panels, said light source projecting direct light rays upon one of said panels, means for cutting off the direct light rays from said light source on to the other of said panels, and a reflector cooperatively arranged with respect to said light source and the last-mentioned panel.

3. In a lighting fixture, the combination with a housing provided with outwardly presented light transmitting panels, of light sources arranged within said housing and along the edges of said panels, and a reflector arranged across the opposite edges of said panels, said housing being provided with a light transmitting panel oppositely disposed with respect to said reflector.

4. In a lighting fixture, the combination with a housing comprising light-transmitting lateral walls, a light-transmitting bottom wall, and a light-reflecting top wall, of light sources arranged adjacent the adjoining edges of said lateral and bottom walls, and another light source arranged adjacent said reflecting surface.

5. In a lighting fixture, the combination with a housing provided with two light-transmitting panels arranged at angle to each other and having contiguous edges, of a light source arranged in the angular space between said panels and adjacent to one edge of one of said panels, a reflector disposed beyond the opposite edge of that panel and cooperatively arranged with respect to said light source and the other of said panels, and means for cutting off the direct light rays from said light source on to the last-mentioned panel.

6. In a lighting fixture, the combination with a housing comprising lateral walls provided with light-transmitting panels, of light-sources arranged within said housing and along the edges of said panels, and other light-sources centrally disposed with respect to the plane of the upper edges of said light-transmitting panels.

7. In a lighting fixture, the combination with a housing provided with light-trans-

mitting panels in the side and bottom walls of said housing and an inner reflecting top wall, light sources arranged adjacent to the bottom wall of said housing and symmetrically with respect to the vertical axis of said housing, said light sources being disposed to project upwardly-directed oblique light rays on said side wall panels, means for cutting off the direct light rays from said light sources on to the bottom wall panels, and light-emitting means centrally disposed with respect to said side-wall and bottom-wall panels, said inner reflecting top wall being cooperatively arranged with respect to said light sources and said bottom wall panels.

8. In a lighting fixture, the combination with a housing having side and bottom walls respectively provided with light-transmitting panels, of a light-source arranged within said housing to project direct light rays thru said side wall panel, a reflector cooperatively arranged with respect to said light-source and the bottom wall light-transmitting panel, and means for cutting off the direct light rays from said light source to said bottom wall panel.

9. In a lighting fixture, the combination with a housing provided with two light-transmitting panels, of a light-source arranged within said housing to the project direct light rays thru both of said panels, another light-source arranged within said housing to project direct rays of light thru one of said panels, a reflector cooperatively arranged with respect to the last-mentioned light-source and the other of said panels and means for intercepting the direct light rays from said last-mentioned light source to the last-mentioned panel.

10. In a lighting fixture, the combination with a housing provided with light-transmitting panels in the side and bottom walls thereof and an inner reflecting top wall, light sources arranged adjacent to the bottom wall of said housing to project upwardly-directed oblique light rays on said side wall panels, means for cutting off the direct light rays from said light sources on to the bottom wall panels, and light-emitting means centrally disposed with respect to said side-wall and bottom-wall panels and adjacent to said inner reflecting top wall.

11. In a lighting fixture, the combination with a housing provided with multiple light-transmitting panels in the side and bottom walls of said housing and an inner reflecting top wall, of a multiple lamp-socket depending from the center of said reflecting top wall, lamps mounted in the lamp-receptacles of said multiple lamp-socket, said lamps being presented toward the side-wall panels respectively, light sources arranged adjacent to the bottom wall of said housing and below the line of

vision at the bottom of said side-wall panels, and means for cutting off the direct light rays from said light sources on to the bottom wall panels.

- 5 12. In a lighting fixture, the combination with a housing provided with two light-transmitting panels, of two light sources within said housing, one of said light-sources being arranged adjacent the top wall of said housing and the other light-source being arranged along the edge of one of said panels, a reflector cooperatively arranged with respect to the other light-source and one of said panels, and means 10 for intercepting the direct light rays from the last said light-source to the last mentioned panel.

13. In a lighting fixture, the combination with a housing provided with light-transmitting panels, of light-sources arranged along the edges of said panels, other light-sources arranged opposite to said panels, means for intercepting the direct light rays from the first-mentioned light-sources to 20 said panels, and a reflector arranged opposite to said panels and first-mentioned light-sources and centrally with respect to all of said light-sources.

14. In a lighting fixture, the combination with a housing provided with a light-reflecting top wall and light-transmitting side and bottom walls, a light-source arranged within said housing to throw direct light rays thru the side wall of said housing and reflected rays thru the bottom wall of said housing, and means for cutting off the direct rays of light from said light-source thru the bottom of said housing.

15. The combination with a lamp-housing provided with lateral and bottom light-transmitting panels and a top reflecting wall, of lamp-supporting bases arranged along the adjoining corners between said lateral and bottom panels, said lamp-supporting bases being inclined upwardly and inwardly from said adjoining corners between said lateral and bottom panels, lamps mounted on said lamp-supporting bases and between said base and lateral panels, and 40 50 a lamp depending from said top reflecting wall.

16. In a lighting fixture, the combination with a housing provided with a bottom

frame comprising a plurality of radially arranged supporting members, of a plurality of light-transmitting panels provided with radial edges supported by said supporting members, lamps mounted upon said supporting members, said supporting members being provided with laterally-presented flanges arranged to cut off the direct rays of light from said lamps to said panels, an inner top reflecting wall adapted to reflect the light from said lamps to said panels, and side wall light-transmitting panels 55 60 65 arranged between the outer ends of said supporting members and said inner reflecting top wall.

17. In a lighting fixture, the combination with a housing provided with a bottom frame comprising a plurality of radially arranged supporting members, of a plurality of light-transmitting panels provided with radial edges supported by said supporting members, lamp-sockets mounted at opposite ends of each of said supporting members, line-filament lamps mounted in said lamp sockets, light-intercepting plates mounted on said supporting members, said plates being arranged on opposite sides of said 70 75 80 lamps for cutting off the direct rays of light from said lamps to said panels, an inner top reflecting wall adapted to reflect the light from said lamps to said panels, and side wall light-transmitting panels arranged between the outer ends of said supporting members and said inner reflecting top wall.

18. In a lighting fixture, the combination with a housing provided with a bottom frame comprising a plurality of radially arranged upwardly-diverging supporting members, of a plurality of light-transmitting panels provided with radial edges supported by said supporting members, lamps mounted upon said supporting members, said supporting members being provided with laterally-presented flanges arranged to cut off the direct rays of light from said lamps to said panels, an inner top reflecting wall adapted to reflect the light from said lamps to said panels, and side-wall light-transmitting panels arranged between the upper ends of said supporting members and said inner reflecting top wall.

WILLIAM H. SPENCER.
